CONSTANT LEVEL LUBRICATING DEVICE

Filed April 8, 1931

Inventor:

Koichi Aoki,

by *Charles V. Tulla*
His Attorney.

UNITED STATES PATENT OFFICE

KOICHI AOKI, OF TOKYO, JAPAN, ASSIGNOR TO GENERAL ELECTRIC COMPANY, A CORPORATION OF NEW YORK

CONSTANT LEVEL LUBRICATING DEVICE

Application filed April 8, 1931, Serial No. 528,634, and in Japan May 21, 1930.

My invention relates to constant level lubricating devices, more particularly to lubricating devices of the type provided with a storage reservoir containing oil below atmospheric pressure from which flow of oil to a bearing is regulated by a vent controlling the admission of air to said reservoir in response to drop in level of the oil feeding said bearing.

10 Constant level oil lubricating devices employing a casing comprising an oil storage reservoir and an oil supply chamber interconnected by vents and passages in a manner well known in the art for maintaining the oil level within the supply chamber constant have heretofore been constructed by a single casting with the result that air holes or other imperfections may exist in the casting causing failure or imperfect functioning of the oil feed.

A principal object of my invention is the provision of an improved and simplified lubricating device of the character above referred to which shall require a minimum 25 number of parts and may be constructed easily and at low cost.

My invention will be more fully set forth in the following description referring to the accompanying drawing, and the features of 30 novelty which characterize my invention will be pointed out with particularity in the claim annexed to and forming a part of this specification.

Referring to the drawing, Fig. 1 is an elevational cross-sectional view of a bearing lubricating device embodying my invention and Fig. 2 is a fragmentary sectional view further illustrating the structure shown in Fig. 1.

40 Referring to Fig. 1, the lubricating device embodying my invention comprises a housing structure 1 supporting the bearing 2 of the shaft 2' and provided with a partition 3 dividing the housing into an upper storage reservoir 4 and a lower oil supply chamber 5. The lubricating oil within the supply chamber 5 is normally maintained at the indicated level 6 and is fed to the bearing 2 in a manner well known in the art by absorb- 45 ent material 6' placed within the well 7. The

housing structure 1 is formed in any preferred manner, as by casting or by welding the walls to form a fabricated structure.

The passages and vents interconnecting the reservoir 4 and the chamber 5 for admitting oil to the lower chamber and controlling the oil level therein are formed in a unit comprising a plug-like member or unit 8 mounted within the housing and extending through the partition 3 into the lower chamber 5. The unit 8 is mounted within the housing in any suitable manner, as by screw threaded engagement with the partition and walls of the housing as indicated. The unit is provided with a longitudinal bore 9 open at its upper end to atmosphere and communicating at its lower end with the supply chamber 5, and, through the passage 10 with the lower part of the reservoir 4, as clearly illustrated in Fig. 1. Accordingly, the reservoir 55 may be refilled in a well known manner by inserting a nozzle or filling pipe into the bore 9 closing off communication with the chamber 5 to force oil through the passage 10 into the storage reservoir. Also, during normal 60 operation of the lubricating device oil may flow from the reservoir 4 through the passage 10 into the supply chamber 5.

For the purpose of maintaining substantially constant the oil level within the chamber 5 the unit 8 is also provided with a vent 11, referring to Fig. 2, communicating with the upper part of the storage reservoir 4 and the supply chamber 5. The vent 11 terminates at its lower end in an adjustable nipple 12, the position of the outlet of the nipple determining the oil level within the chamber 5. When the oil level drops below the nipple 12 admitting air through the vent 11 to the upper part of the storage reservoir, oil therein is free to flow by gravity through the passage 10 into the chamber 5 until the oil again rises to close the lower opening of the vent 11. Oil feed from the reservoir 4 thereby ceases by reason of the partial vacuum above the oil 85 in the reservoir, the oil within the chamber 5 of course being subject to atmospheric pressure at all times.

In the construction above described, the unit 8 may be separately machined and drilled 90

50

100

to form the oil feed passages and vents and may be of superior quality to that of the housing 1, thereby resulting in an improved lubricating device which, however, may be constructed at low cost. It will likewise be noted that the only apertures within the housing 1 are those required for the insertion of the unit 8, the opening in the lower wall of the housing in fact being unnecessary since the upper wall and partition 3 may provide suitable support and mounting for the unit which may simply rest on the bottom of or extend into the supply chamber 5.

It should be understood that my invention is not limited to specific details of construction and arrangement thereof herein illustrated, and that changes and modifications may occur to one skilled in the art without departing from the spirit of my invention.

20 What I claim as new and desire to secure by Letters Patent of the United States, is:

A lubricating device for a bearing comprising a storage reservoir containing oil below atmospheric pressure, a supply chamber disposed beneath said reservoir for feeding oil to said bearing, and a plug-like member mounted within said reservoir and chamber, said member being provided with a longitudinal bore normally communicating with atmosphere at one end and through communicating passages with both the storage reservoir and the supply chamber at the other end arranged so that said reservoir may be refilled directly through said bore, and, during normal operation oil may feed from said reservoir into said supply chamber, said member likewise being provided with a vent interconnecting said reservoir and supply chamber causing feed of oil into said chamber only in responsive to predetermined lowering of the oil level therein.

In witness whereof, I have hereto set my hand.

KOICHI AOKI.
